EDWARD R. HOLDEN, OF LOS ANGELES, CALIFORNIA.

APPARATUS FOR THE ELECTRIC DISSOLUTION AND PRECIPITATION OF METALS.

1,295,752.

Specification of Letters Patent. Patented Feb. 25, 1919.

Application filed April 17, 1917. Serial No. 162,689.

To all whom it may concern:

Be it known that I, EDWARD R. HOLDEN, a citizen of the United States, residing at Los Angeles, in the county of Los Angeles and State of California, have invented new and useful Improvements in Apparatus for the Electric Dissolution and Precipitation of Metals, of which the following is a specification.

10 This invention relates to an improved apparatus for electro-chemically dissolving metals and their compounds from ores, and the precipitation and recovery of the metals in a rapid, economical and efficient manner.

15 The essence of this invention resides in the provision of means whereby a plurality of independent and distinct electric currents of different E. M. F. are distributed and disseminated simultaneously in different parts 20 of an electrolyte.

The present invention is a division of my co-pending application for a process of electro-chemical dissolution and precipitation of metals, filed October 10th, 1916, Serial No. 25 124,902, which covers the process carried out by means of the apparatus claimed in the present application.

20 In the accompanying drawings, which form a part of this specification, I have illustrated a convenient and practical embodiment of my invention, and in which:

Figure 1 is a view in vertical section, partly in elevation, of an apparatus employed in carrying out my process, showing 35 a part of the electrical device in diagram.

Fig. 2 is a diagrammatic view illustrating the electric circuits and the manner of distributing the electric current throughout an electrolyte.

40 Fig. 3 is a view in horizontal section on a reduced scale, as seen on the line 3—3, of Fig. 1.

Fig. 4 is a detail in plan of the revolving resistance coil carriage and the wiper contact for delivering electric current thereto.

45 To carry out the action above referred to in the most advantageous manner, I preferably use a circular tank of any reasonable number of feet in diameter, and of a depth

sufficient to hold large quantities of solution containing metals in solution. 50

In Figs. 1 and 2 of the accompanying drawings, I have illustrated by a vertical sectional view, and in diagram, one embodiment of a tank showing fully the manner of wiring; the resistance coils necessary for the regulation of the current; the various anodes and their respective distances from the cathode; a non-conducting shaft, said shaft being constructed of any suitable material, 55 such as hard wood, hard rubber or other material, not affected by acid or alkaline solutions, nor electrolysis, together with a copper, mercury or other negative cathode on the bottom of the tank. 60

More specifically in the drawing, A indicates a tank of any suitable material, preferably wood, about six feet in diameter, and twelve feet in depth, although other sizes may be found advantageous. In this tank a 70 vertical shaft B of non-conducting material is mounted, and throughout its entire height at equal distances apart, carries a number of metallic paddles as anodes numbered from 1 to 9; anode 1 being placed just above a 75 cathode C, comprising a copper or other metallic plate or mercury arranged to cover the bottom of the tank. The paddles are here shown as comprising four blades to a set; each set constituting a separate anode. 80 By repeated experiments I have found that in a tank twelve feet deep filled with a solution containing metals in solution, that the best electrolytic precipitation is obtained when the metallic anodes are set about twelve 85 to fifteen inches apart; the lowest anode 1 being six to twelve inches, more or less, above the cathode C. The shaft is rotated by gearing D or other suitable means.

On the upper part of the non-conducting 90 shaft is a circular metallic contact ring E connected with a positive current of electricity, through a wiper contact F, connected with a conductor G, leading from one terminal of a source of electrical supply or 95 generator H; a conductor I leading from the other terminal of the generator to the cathode C. On the lower end of the metallic

contact ring E and attached thereto is a circular disk J of hard rubber or other non-conducting substance. Resting upon and attached to the disk J are separately wound 5 individual resistance coils 1^a to 9^a as shown in Fig. 2, there being one resistance coil for each of the anodes attached to the shaft. The top of each resistance coil is connected with the contact ring E and the positive 10 current of electricity passes from the contact ring into each resistance coil, the lower ends of which are resting on the disk J and each coil is connected with its own separate insulated wire or conductor 1^b to 9^b, leading 15 down through the electrolyte to an anode. Each one of these separate resistance coils is so wired as to convey a regulated and controlled volume of electricity to the anode to which it is attached; the separate 20 coils being graded in decreasing or increasing degrees of resistance according to the distance of the anodes from the cathode, for example, coil 1^a connecting with the lowermost anode 1 is of greatest resistance 25 and coil 9^a connecting with the uppermost anode of the least resistance, with the intermediate coils stepped down in uniform degrees of reduced resistance as the distance of the anodes from the cathode is increased, 30 thus introducing an independent electric current through each anode of such amperage as will overcome the added resistance caused by the distance of each anode from the cathode. Each anode thus becomes an 35 independent one, capable of disseminating the necessary amount of current density through the solution to overcome the resistance caused by the distance of each anode from the cathode whereby the electric current 40 passing into the electrolyte is distributed throughout the whole solution in such a manner that the metals in solution are immediately and uniformly liberated into metallic ions from their compound condition 45 and are precipitated on the cathode; the detailed operation of which is hereafter more fully explained.

At the bottom of the tank A is a draw off pipe K, for the purpose of drawing off the 50 mercury cathode or removing precipitates from the surface of any cathode used.

The shaft B extends through the bottom of the tank A and is supported by an ordinary stuffing box and the end of the shaft 55 operates in an ordinary ball bearing box.

The anodes described and attached to the non-conducting shaft, are made of any material best suited to the dissolution and precipitation of the metals in solution and are 60 positive to the metallic substances used as a cathode and while revolving in the tank, also serve as agitators for the solution, and

through the separate resistance coils which are in contact with the wires leading to each anode, disseminate throughout the electrolyte, between each anode and the cathode, the different amperages necessary in every part of the solution to establish the most effective precipitating potential throughout the whole solution. 65

For the information of those not versed in the art of direct current dissemination through an electrolyte containing metals in solution and for their precipitation and recovery and to increase the efficiency and potential conditions necessary in conducting electricity into a liquid, and for clearly exemplifying the improvement in the method of disseminating varying quantities of E. M. F. to separate anodes throughout the 70 electrolyte, I herewith append the results of the following tests conducted for the purpose of advancing the art and to illustrate the improvements over those indicated in my previous Letters Patent granted April 25th, 1916, numbered 1,181,077, and entitled "Process of treating ores bearing 75 precious metals".

I found by experiment in a tank three feet in diameter and nine feet in depth, containing a solution carrying gold and silver in solution, with sufficient sodium chlorid present to establish the necessary conductivity and a current of positive electricity passing down through the electrolyte, by means of 80 separate wires attached to a contact ring above, and connected with a number of anodes attached to a non-conducting shaft, but without using the resistance coils hereinbefore described, that the density of the current between the lowest anode 1 and the cathode was 690 times greater than the density of the current surrounding the highest anode 9 at the top of the solution and that the several anodes from 2 to 9 inclusive indicated a constantly decreasing amount of 85 amperes in proportion to their increased distance from the cathode and had therefore, only a trace or at best but a feeble dissolving and precipitating action on the metallic 90 compounds in solution above the lowest anode. 10

In the above experiment the shaft was revolved with the anodes set about one foot apart; the bottom anode 1 being six inches 11 above the cathode.

The same unequal densities prevailed throughout the solution when a direct, undivided and unaltered current of electricity was conducted into the electrolyte through 12 a conducting shaft on which a number of anodes set in the same manner as above described were attached.

Each of the anodes, above the lowest one,

which was in closest contact with the cathode, showed a uniform proportional decrease in amperes, the density of the current between the lowest anode 1 and the cathode was 4.14 5 amperes per square foot of cathode surface, while the density of the current just below the top anode 9 was only .006 ampere per square foot of cathode surface.

The following table gives the registered 10 ampere readings, indicated on a testing ammeter, per square foot of cathode surface, as registered by each anode separately, beginning with the lowest anode 1 and showing a decreased potential at each anode in 15 proportion to the distance between each anode and the cathode:

	Volts.	Individual anode readings.	Distance from cathode.
		Ampères.	
20			
Anode No. 9.....	12	.006	8' 6"
Anode No. 8.....	12	.009	7' 6"
Anode No. 7.....	12	.014	6' 6"
Anode No. 6.....	12	.026	5' 6"
Anode No. 5.....	12	.041	4' 6"
25 Anode No. 4.....	12	.060	3' 6"
Anode No. 3.....	12	.140	2' 6"
Anode No. 2.....	12	.430	1' 6"
Anode No. 1.....	12	4.140	6"

The following experiments are herewith 30 set forth for the purpose of comparison and to show the detailed operation of and advantages derived by the present process. So far as I am aware a current of electricity has never been disseminated and distributed 35 throughout a solution by means of a plurality of anodes, through a conducting or non-conducting shaft, and therefore, I deem it necessary to set forth the operation in detail so that the improvement which I 40 claim as new and useful can be fully understood by those desiring to take advantage of this process.

An experiment was conducted in the 45 above tank which contained 4,500 lbs. of 20% potassium cyanid solution, carrying gold and silver in solution. The solution also contained the necessary amount of sodium chlorid to establish the conductivity required.

The current was then led through the 50 contact ring directly to each anode, passing thence through the electrolyte to the cathode for the purpose of precipitating the gold and silver out of the solution and this operation 55 continued for six hours. After each hour a sample of the solution was drawn through a pet cock in the side of the tank just below anodes 1, 5 and 9.

The solution obtained below anode 1 at the 60 end of the first hour, showed that the gold and silver value of the solution had decreased 46% per ton of solution. The

sample taken simultaneously below anode 5 showed that the gold and silver value had decreased 36% per ton of solution, while the 65 sample taken simultaneously below anode 9 had decreased only 6% per ton of solution. Samples taken at the end of the second—third—fourth—fifth and sixth hours, showed that the precipitation occurred 70 most rapidly during the first hour, but that the action continued proportionately the same during the remaining five hours at all the respective anodes.

The sample taken below anode 1 at the 75 end of the sixth or final hour showed that the gold and silver value of the solution had decreased 98.2% per ton of solution, while the sample taken simultaneously below 80 anode 5 showed the gold and silver value had decreased 75% per ton of solution, while the sample taken simultaneously below anode 9 had decreased only 50% per ton of solution. The entire contents of the 85 tank was then withdrawn and the solution thoroughly mixed and showed a total precipitation of only 74.4 of the gold and silver, from the original solution.

Another experiment was then made with 90 a similar solution carrying the identical values in gold and silver per ton. The resistance coils heretofore described were then put in contact on disk J and connected with the contact ring E and the lead paddles as anodes. The resistance coils were wound with climax wire in such a manner as to deliver to each anode the necessary E. M. F. so that the potential at each anode was altered and maintained in the electrolyte in proportion to its distance from the cathode, thereby regulating the potential between each anode and the cathode, and producing throughout the solution, from the top to the bottom, the required amperage to establish the necessary potential simultaneously in all parts of the solution to decompose and precipitate the metals from their compounds, with the following result:

	Volts.	Individual anode readings.	Distance from cathode.
		Ampères.	
110			
Anode No. 9.....	12	2.50	8' 6"
Anode No. 8.....	12	2.36	7' 6"
Anode No. 7.....	12	2.22	6' 6"
Anode No. 6.....	12	2.08	5' 6"
Anode No. 5.....	12	1.94	4' 6"
Anode No. 4.....	12	1.83	3' 6"
Anode No. 3.....	12	1.70	2' 6"
Anode No. 2.....	12	1.62	1' 6"
Anode No. 1.....	12	1.50	6"

115 After the above regulated current had been disseminated throughout the electrolyte for one hour samples of the solution corresponding to those taken in test one were

drawn just below anode 1, 5 and 9. The solution taken below anode 1 had decreased in value in gold and silver 48% per ton of solution. The sample taken simultaneously just below anode 5 showed the gold and silver value of the solution had decreased 44% per ton of solution, while the sample taken at the same time, just below anode 9 had decreased 35% per ton of solution. Samples taken at the end of the second—third—fourth—fifth and sixth hours showed that the precipitation was proportionately uniform at all the respective anodes. The samples taken at the end of the sixth or final hour showed that the gold and silver value of the solution had decreased below anode 1, 99.9% per ton of solution, while the sample taken simultaneously just below anode 5 showed the gold and silver value had decreased 99.7% per ton of solution, while the sample taken simultaneously just below anode 9 showed the gold and silver value had decreased 99.5% per ton of solution.

A continuation of the operation of the current through the electrolyte for a longer period would have precipitated the trace of gold and silver remaining in the solution, but the time required and the current costs in recovering same, commercially precluded carrying the operation further.

The second table above referred to shows a regulated decrease of amperage from the bottom to the top. The applicant does not desire, however, to limit himself to the method of regulating the amperage so that the highest amperage is at the bottom and the lowest at the top, as indicated by this table, but may regulate the amperage that the values of the table may be reversed, and the highest amperage will be at the top and the lowest at the bottom, or the amperage may be substantially equal at each anode. The preferred method is to have the highest amperage at the top, decreasing toward the bottom, but my method broadly contemplates regulation of the amperage at different anodes in the solution.

The use of a non-conducting shaft or one entirely constructed of non-conducting material and carrying no current into the electrolyte, makes possible the dissemination of different E. M. F. through various anodes at different points in the solution, with the result above described.

The above described method of distributing and disseminating an electric current, is also adaptable to and greatly accelerates the dissolution of metals and their compounds from ores in (for example) a cyanid

electrolyte by the liberation of cyanogen, at

the cathode, according to the following well known equations:

thereby regenerating the solvent solution and maintaining comparatively uniform and constant strength therein, throughout the 75 operation, which results in bringing about a very much more rapid and efficient dissolution of the metals and their compounds than can be obtained if the electric current is not distributed and disseminated by 80 means of a plurality of anodes throughout the electrolyte.

Similar regeneration of solvent is brought about when bromin, chlorin, sulfate or other solvent is used.

85

I am aware of the fact that patents have been issued in this and other countries for the use of a current of electricity in an electrolyte containing metals for the purpose of dissolution or precipitation, or both, and 1 90 do not claim anything by reason of any such action, but what I do claim as new and desire to secure by Letters Patent, is:

1. An apparatus for treating solutions containing metals, comprising a cylindrical tank, a vertical non-conducting shaft mounted therein, means for rotating said shaft, a plurality of agitator arms fast to said shaft and arranged in sets one above the other, a cathode at the bottom of said tank, a plurality of independent electric conductors leading to said sets of agitator arms, there being one conductor for each set, said arms constituting anodes, and means for independently controlling the E. M. F. of the 100 current delivered to each set of anodes. 105

2. An apparatus for treating solutions containing metals, comprising a tank, a vertical shaft mounted therein, means for rotating said shaft, a cathode, a plurality of agitator arms fast to said shaft and arranged at various distances from said cathode, a plurality of independent conductors leading to said agitator arms, said arms constituting anodes, and means for independently controlling the E. M. F. of the current delivered to each anode. 110 115

In testimony whereof I have signed my name to this specification.

EDWARD R. HOLDEN.
